UNITED STATES PATENT OFFICE.

DANIEL J. McCARTHY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

WARNING-SIGNAL FOR RAILWAY-CROSSINGS.

1,197,218.

Specification of Letters Patent.

Patented Sept. 5, 1916.

Application filed May 10, 1915. Serial No. 26,925.

To all whom it may concern:

Be it known that I, DANIEL J. McCARTHY, a citizen of the United States, residing at Wilkinsburg, in the county of Allegheny and State of Pennsylvania, have invented certain new and useful Improvements in Warning-Signals for Railway-Crossings, of which the following is a specification.

My invention relates to warning signals for railway crossings.

I shall describe one form of signal embodying my invention and then point out the novel features thereof in claims.

In the accompanying drawings, Figure 1 is a perspective view of a grade intersection of a railway and a highway, adjacent which is located one form of warning signal embodying my invention. Fig. 2 is a view showing in elevation the mechanism of the signal shown in Fig. 1. Fig. 3 is a view showing part of Fig. 2 on a larger scale. Fig. 4 is a view showing a section of Fig. 3 on line IV—IV, looking in the direction of the arrows. Fig. 5 is a bottom plan view of Fig. 3. Fig. 6 is a view showing part of Fig. 2 on a larger scale. Fig. 7 is a view showing a side elevation of the parts shown in Fig. 6. Fig. 8 is a fragmental view of a portion of the apparatus shown in Fig. 3 looking toward the left. Fig. 9 is a cross sectional view of part of the mechanism shown in Figs. 2, 3 and 5. Fig. 10 is a diagrammatic view showing one form and arrangement of control circuits for the signal shown in Fig. 1.

Similar reference characters refer to similar parts in each of the several views.

Referring first to Fig. 1, I have here shown a railroad track R crossing a highway H. Near the crossing and visible from the highway at a distance from either side of the crossing is a warning signal S, which as here shown comprises a casing 1 provided with a window 2 on both sides and mounted by means of a bracket 3 on a post 4. By mechanism contained in casing 1 a moving beam of light, preferably red, is made to shine through window 2 when a train approaches the highway. This light indication is very conspicuous, as I shall explain hereinafter, and constitutes an effective warning to traffic that a train is approaching the crossing. The light is automatically

extinguished when the train passes the highway.

I shall now describe the apparatus by which the above effects are obtained.

Casing 1 contains, see Figs. 2 to 5, a carriage C adapted to travel on a track T, which as here shown comprises a rail 5 on which the carriage runs and two guide rails 6 and 7. Brackets 8 and 9 are fastened on the threaded extremities of these rails by means of nuts 11 so that rail 5 is held parallel to and above the middle line between rails 6 and 7, as best shown in Figs. 4 and 5. Track T is pivotally mounted on a base 29, as I shall now explain with reference to Figs. 2, 6 and 7. Angle irons 12 and 13 are fastened to rails 6 and 7 respectively by means of screws 14. A reinforcing plate 22 is riveted to the under side of the angle irons in order to make this construction more rigid. Two plates 15 and 16 are secured to the angle irons by means of rivets 17 and 18 are provided at their lower ends with holes through which is passed a pin 18. A bracket 19 fastened to base 29 by means of screws 21 supports pin 18; thus the entire track T can be turned about shaft 18 as a pivot. Adjacent the right end of rail 6, see Fig. 2, is mounted a clamp 24 which is connected by means of a link 25 to a crank arm 26. A motor M is provided to revolve crank 26 through the medium of worm gearing 27. It is apparent that rotation of crank 26 causes track T to rock about pin 18 as a center with a periodicity that depends upon the motor speed and gear ratio.

Carriage C, see Figs. 3 to 5, is suspended by means of a bracket 33 from the axle 32 of a wheel 31, the rim of which is grooved to fit the surface of rail 5. Bracket 33 is made in two parts, a U-shaped portion 33^a and a straight portion 33^b as shown in Fig. 4. A hole 34 is drilled into the upper ends of each of these portions and the ends of shaft 32 are inserted therein; then the two portions of the bracket are secured to each other by means of screws 35. A frame F, comprising an upper bar 36 and a lower bar 37 secured to bar 36 by means of standards 38 and screws 41, is suspended from bracket 33 by means of screws 39, so that frame F is placed at an angle to track T, as best shown in Fig. 5. Guide rollers 42 for preventing

lateral swaying of carriage C are mounted on studs 43 riveted to the under side of bar 37, so that they engage guide rails 6 or 7 when the carriage swings to one side or the other. The carriage is guided also by two additional wheels 45 which are adapted to roll on the under side of bar 5 and which are journaled on shafts 46 riveted at one end to bars 47 secured to upper bar 36 of frame 5

10 F. It is apparent from this method of suspension of carriage C that, when track T is tilted, carriage C rolls from the higher end of the track to the lower end, and by rocking the track with the right periodicity, carriage C can be made to roll alternatively from one end of the track to the other. To absorb the momentum of the carriage when it reaches either end of the track, I provide spring buffers 51 on each end of track T.

15 20 With reference to Figs. 3 and 8, buffer 51 comprises a cylindrical tube 52 screwed into a plate 53 fixed to the upper end of bracket 8 by means of nut 11. A plug 54 screwed into the left end of tube 52 serves as a stop 25 for a spring 55, the other end of which bears on a plunger 58 adapted to reciprocate in tube 52. A pin 56 through the right end of tube 52 and passed through a slot 57 in plunger 58 limits the distance through which 30 plunger 58 reciprocates. Spring 55 biases plunger 58 to project from tube 52. When the track is tilted so that the carriage approaches one of the buffers the end of arm 47 engages plunger 58 so that spring 55 is compressed, and the carriage is smoothly brought to rest. The spring expands when the tilt of the track is reversed and gives the carriage an impetus so that it starts off rapidly to roll in the reverse direction.

35 40 Frame F of carriage C serves as a support for two mirrors mounted thereon in a manner, which I shall now describe with reference to Figs. 3, 4 and 5. A plate 76 is pivotally mounted in frame F at its lower end 45 by means of a stud 77, riveted to plate 76 and journaled in a thrust ball bearing 75 in bar 37, and at its upper end by means of a shaft 73 fixed to plate 76 and journaled in a ball bearing 74 in bar 36. Mirrors 78 and 50 55 79 are fixed to the faces of plate 76 by means of brackets 81 secured to plate 76 by screws 82. For rotating the mirrors I provide a pinion wheel 72 keyed to shaft 73 and adapted to engage gear wheels 65 and 66 55 mounted loosely on shaft 32. Ratchets 63 and 64 are fixed adjacent the ends of shaft 32, so that they are rotated when wheel 31, which is keyed to shaft 32 by a pin 61, rolls on rail 5. A pawl 67 (see Fig. 3) is pivoted 60 on wheel 65 and biased by a spring 71 to engage ratchet 63. The teeth of ratchet 63 are shaped as shown in Fig. 3, so that ratchet 63 drives wheel 65 when rotated in a clockwise direction, *i. e.* when the carriage 65 travels from left to right. Similarly, a pawl

68 on wheel 66 is adapted to engage ratchet 64, the teeth of which are shaped so that ratchet 64 drives wheel 66 when rotated in a counter-clockwise direction, *i. e.* when the carriage travels from right to left. Since 70 wheels 65 and 66 engage pinion 72 on opposite sides, it is evident that, as the carriage rolls alternatively from one end of the track to the other, mirrors 78 and 79 are rotated continuously in one direction, counter-clockwise when viewed as in Fig. 5. Two beams of light are thrown on mirrors 78 and 79 by means of lamps 85 and 86 in casings 87 (see Fig. 2) secured to brackets 8 and 9. Each beam of light is preferably made intense and its rays nearly parallel by any suitable means, for example by an optical train of convex lenses 91 and 92 shown in Fig. 9, which is a cross sectional view of one casing 87. The light emitted from casings 87 is preferably colored red by means of a plate of red glass 93, inserted in each casing 87.

75 80 85 To explain the light effect produced by the signal when operating and viewed from the highway, assume for the present that mirrors 78 and 79 do not rotate as carriage C moves on track T, but are fixed on the carriage at an angle of 45° to the track. Then the light from lamps 85 and 86 falls 90 on mirrors 79 and 78 respectively and is reflected therefrom at right angles to track T, so that an observer sees a reciprocating light behind window 2 when the signal is operating, provided the observer is within 95 the angular limits defined by the spread of the beams of light. But it is of great importance that the indication of signal S may be seen from all parts of the highway adjacent the railway crossing so that with the 100 mirrors stationary with respect to the carriage it would be necessary to use a widely divergent beam of light. Since it is also necessary that the light be of a high candle power in order that it may be noticed in 105 daylight, the power consumption of such a signal would be very high. By rotating the mirrors this difficulty is overcome as I shall now explain. Suppose first that the carriage remains stationary while the mirrors 110 115 are rotated. It is well known that the reflection of a beam of light incident on a revolving mirror is rotated through twice the angle through which the mirror is turned, so that the reflected beam is revolved through 120 360° when the mirror is turned through 180°. Consequently, with two lights and two mirrors placed back to back the signal sends out two revolving beams of light in opposite directions, and an observer viewing this signal from any part of highway H sees four flashes of light emitted from window 2 during every revolution of the mirrors.

125 130 The signal I have described combines the

reciprocating mechanism with the rotating mechanism, with the result that an observer approaching the signal from either side sees, when the signal is operating, an apparently flickering light swinging behind window 2. The intensity of this light combined with its peculiar movement and flicker makes it ostentatious to a high degree and very suitable for a warning signal.

10 The control circuits for signal S I have shown in Fig. 10, wherein reference characters 91 and 92 designate the rails of railroad track R on which traffic moves in the direction of the arrow. N designates a track 15 section insulated from the rails at either end of the section by insulated joints 93. Section N is equipped with a track circuit which comprises a source of potential, here shown as a battery 94, and a relay 95. Signal S is 20 controlled by relay 95, the circuit being: from a battery 96, through wire 97, back contact 98 of relay 95, wire 99, lamp 85, wire 101, lamp 86, motor M, wire 102 to battery 96. With no train on section N, relay 95 is 25 energized so that the back contact is open and signal S is inoperative. When a train enters section N, however, back contact 98 is closed, and motor M is energized and rocks track T so that carriage C is reciprocated. At the same time lamps 85 and 86 30 are illuminated, and the signal is thus operated to give its warning indication as described hereinbefore. When the train leaves section N relay 95 is reenergized, and breaks 35 contact 98, so that the signal ceases to operate.

Although I have herein shown and described only one form of warning signal embodying my invention, it is understood that 40 various changes and modifications may be made therein within the scope of the appended claims without departing from the spirit and scope of my invention.

Having thus described my invention, 45 what I claim is:

1. A traffic signal comprising a lamp, a mirror adapted to receive light from said lamp, and means for reciprocating said mirror so that the light reflected from said mirror is also reciprocated.

2. A traffic signal comprising a lamp, a mirror, means for projecting a beam of light from said lamp upon said mirror, and means for reciprocating said mirror so that said beam is reciprocated.

3. In combination, a lamp, a carriage, a track for said carriage, a mirror mounted on said carriage, means for projecting a beam of light from said lamp upon said mirror, and means for reciprocating said carriage on said track whereby said beam of light is reciprocated when reflected from said mirror.

4. In combination, a lamp, a carriage, a 65 rail on which said carriage runs, a mirror

on said carriage and adapted to receive light from said lamp, and means for rocking said rail whereby said carriage is reciprocated.

5. In combination, a lamp, a carriage, a rail, means for movably mounting said carriage on said rail, a mirror on said carriage adapted to receive light from said lamp, and electromagnetic means for rocking said rail so that said carriage rides back and forth on said rail, whereby the light reflected from said mirror is caused to reciprocate.

6. A traffic signal comprising a lamp, a mirror, and means for rotating said mirror so that light from said lamp is reflected by said mirror as a rotating beam.

7. In a railway crossing signal, a rail, a carriage adapted to ride thereon, means for reciprocating said carriage on said rail, a mirror on said carriage, mechanism whereby said mirror is rotated continuously in one direction when said carriage is reciprocated, and a lamp adapted to project a beam of light on said mirror, whereby said beam is reflected and given simultaneously an oscillating and a rotary motion.

8. A traffic signal comprising a mirror, means for projecting a beam of light upon said mirror, and mechanism for rotating and reciprocating said mirror simultaneously, so that said beam of light when reflected from said mirror has simultaneously a rotary and an oscillating motion.

9. In combination, a mirror adapted to reflect light from both sides, means for projecting a beam of light on said mirror, and means for giving said mirror simultaneously an oscillating and a rotary motion.

10. In combination, a track, a carriage adapted to be reciprocated thereon, a mirror on said carriage adapted to be revolved, and a lamp for throwing a beam of light on said mirror.

11. In combination, a track, a carriage on said track, means for reciprocating said carriage, a mirror on said carriage adapted to reflect light from both sides, means for rotating said mirror, and a lamp for throwing a beam of light on said mirror.

12. In combination, a track pivotally mounted, electromagnetic means for rocking said track, a carriage for said track, a mirror on said carriage, means for revolving said mirror when said carriage is moved on said track, and a lamp for throwing light on said mirror.

13. In a railway crossing signal, a mirror, means for reciprocating said mirror, means for rotating said mirror continuously in one direction when the mirror is reciprocated in opposite directions, and a lamp adapted to project a beam of light on said mirror, whereby said beam is reflected and given simultaneously an oscillating and a rotary motion.

14. In a railway crossing signal, a track,

a carriage adapted to reciprocate on said track, a mirror on said carriage; mechanism for rotating said mirror continuously in one direction when said carriage is reciprocated on said track, said mechanism comprising a ratchet and pawl for rotating a gear wheel in one direction when said carriage moves in one direction, another ratchet and pawl for rotating another gear wheel in the opposite direction when said carriage moves in the opposite direction, and a pinion fixed to said mirror and adapted to be engaged

on opposite sides by said gear wheels; and a lamp adapted to project a beam of light on said mirror, whereby said beam is reflected and given simultaneously an oscillating and a rotary motion. 15

In testimony whereof I affix my signature in presence of two witnesses.

DANIEL J. McCARTHY.
